UNITED STATES PATENT OFFICE.

HENRY W. WEATHERS, OF AUGUSTA, GEORGIA, ASSIGNOR OF ONE-HALF TO JAMES P. DOUGHTY, JR., TRUSTEE, OF AUGUSTA, GEORGIA.

GRAPPLE.

Application filed March 2, 1925. Serial No. 12,573.

To all whom it may concern:

Be it known that I, HENRY W. WEATHERS, a citizen of the United States, residing at Augusta, in the county of Richmond and

5 State of Georgia, have invented certain new and useful Improvements in Grapples, of which the following is a specification, reference being had therein to the accompanying drawing.

10 This invention relates to grapples, and more particularly to a grapple designed for use in connection with automobile lifting cranes.

15 One of the principal objects of the invention is to provide a simple inexpensive and efficient grapple, which may be readily attached to an automobile in position to be engaged by the chain hoist or other lifting part of a crane.

20 Another object of the invention is the provision of a grapple which is simply constructed and having means for preventing relative lateral and longitudinal movement of the automobile with respect thereto so that as either end of the machine is lifted there will be no shifting or slippage, thus insuring safety.

25 A further object of the invention is the provision of a device of this character which 30 may be conveniently and rapidly attached to the automobile without the use of bolts, nuts or other loose parts, and which when so attached will effectively prevent longitudinal or lateral movement of the machine 35 with respect to the grapple.

40 Further objects of the invention will appear as the following specific description is read in connection with the accompanying drawings which form a part of this application, and in which:

45 Figure 1 is a perspective view of the front end of an automobile showing the grapple applied thereto and attached to a lifting crane;

50 Figure 2 is a front elevation of the machine with the grapple applied; and

55 Figure 3 is a perspective view of the grapple removed.

50 I have indicated in conventional form at 1 an ordinary automobile, and at 2 I have shown in conventional form a lifting crane employing the usual chain hoist 3 with grapple engaging hook 4. These parts are all old and well known in the art and form 55 no part of the present invention. The char-

acter of the automobile is immaterial and I may employ any suitable form of lifting crane in connection with the grapple which I shall now describe.

The body of the grapple which is generally indicated at 5 is constructed of a single piece of material which may be cold rolled steel or other similar material having the requisite strength and toughness but is preferably formed of a round stock having 60 no edges or corners to mar the finish of the automobile.

In making the device the bar is first bent into a loop forming a hook receiving eye 6 which is arranged approximately in the 70 center as shown. The arms 7 extending in opposite directions from the eye 6 are intermediate their ends bent upwardly in loop form to produce stops or abutments 8. The continuation of the arms beyond the 75 abutments 8 are extended rearwardly at right angle to the front portion and at a point adjacent their terminals are bent into axle engaging hooks 9, each having their immediate terminal formed into an open 80 eye 10 to receive the shanks 11 of retaining pins which are pivotally and slidably movable upon the rearward extensions of the arm 7.

It will thus be seen that the general outline of this grapple is substantially U-shaped in plan and that when applied the arm 7 forms supports 12 which engage beneath the springs adjacent their forward connection with the side bars of the chassis. 90

In applying the device all that is necessary is to place the hooks 9 over the axles as shown in Fig. 1 and throw the locking pins into engagement with the eyes 10. When the forward end is lifted the shoulders or supports 12 contact with the under side of the springs and abutments 8 extend on the outside of each spring and alongside of the side bars of the chassis. In this position the hook 4 of the chain hoist may be engaged 100 with the eye 6 and that end of the automobile to which the grapple is attached raised above the ground.

When this device is employed with a portable crane it will readily be seen that 105 the automobile may be conveniently moved from place to place and also elevated to any desired height making it convenient for a mechanic to operate upon under parts of the car and doing away with pits and 110

skidders. The grapple can also be conveniently used with wrecking trucks for towing a disabled car.

By providing the axle hooks with the locking pins no longitudinal movement in either direction will be possible and by providing the abutments 8 no lateral movement with respect to the hoisting crane is possible. Thus even when the automobile has its ground supported end upon an uneven surface there is no danger of the machine slipping and endangering the life of a workman operating beneath the same.

What I claim is:

15. 1. A one-piece grapple for vehicles comprising axle engaging members, a crane engaging element, and frame supporting portions intermediate said members and element.
20. 2. A grapple for vehicles comprising axle engaging members, a crane engaging element, frame supporting portions intermediate said members, and means to lock the axle engaging members in position on the axle.
25. 3. A grapple comprising axle engaging hooks, means to lock said axle engaging hooks on the axle and a crane engaging element intermediate said hooks and integral therewith.
30. 4. A grapple comprising axle engaging hooks, pivoted locking members for locking the hooks on the axle and an intermediate crane engaging member integral with the hooks.
35. 5. A grapple comprising axle engaging hooks having open terminal eyes, pivoted locking members removably engaged in the eyes to lock the hooks on an axle and an intermediate crane engaging member.
40. 6. A one-piece grapple comprising a body having spaced frame supporting portions, an intermediate crane engaging element, and axle engaging hooks extending at right angles from the frame supporting portions.
45. 7. A grapple comprising a body having

spaced frame supporting portions, an intermediate crane engaging element, axle engaging hooks extending at right angles from the frame supporting portions, and means to lock the hooks on an axle.

8. A grapple for vehicles comprising a body having spaced frame supporting portions thereon, and integral means to prevent lateral movement of a vehicle frame on said portions.

9. A grapple for vehicles comprising a body having spaced frame supporting portions, an intermediate crane engaging element, means for preventing lateral movement of a vehicle frame on said portions and means for preventing longitudinal movement of the vehicle frame with respect to said portions.

10. A grapple for vehicles comprising a body having spaced frame supporting portions, an intermediate crane engaging part, means for preventing lateral movement of a vehicle frame on said portions, and axle engaging elements for preventing longitudinal movement of the vehicle frame on said portions.

11. A grapple for vehicles comprising a body having spaced frame engaging portions, guard elements adjoining said portions and serving to prevent lateral movement of a vehicle frame on said portions, and means for preventing longitudinal movement of the vehicle frame with respect to the said portions.

12. A grapple for vehicles comprising a single piece structure, having a crane engaging element intermediate its ends and spaced frame supporting portions on opposite sides of said element, upstanding guard elements adjoining said portions, and rearwardly extending axle hooks continuing from the guard element and arranged at right angles to the supporting portions.

In testimony whereof I affix my signature.

HENRY W. WEATHERS.
